UNITED STATES PATENT OFFICE.

NELSON D. NICHOLS, OF MINNEAPOLIS, MINNESOTA.

KEY-HOLDER.

1,148,398.

Specification of Letters Patent. Patented July 27, 1915.

Application filed July 3, 1914. Serial No. 848,832.

To all whom it may concern:

Be it known that I, NELSON DE LAUES NICHOLS, a citizen of the United States, residing at Minneapolis, in the county of 5 Hennepin and State of Minnesota, have invented certain new and useful Improvements in Key-Holders; and I do hereby declare the following to be a full, clear, and exact description of the invention, such as 10 will enable others skilled in the art to which it appertains to make and use the same.

This invention relates to key holders, and the primary object of the invention is the provision of a key holder of novel form, 15 which is attached to interior of a door knob and which is provided for receiving the head of a door key, for preventing the turning of the key from the opposite side of the door to which it is inserted, and 20 for preventing the tumbling of the key from the lock.

With the foregoing and other objects in view this invention consists in such novel features of construction, combination and 25 arrangement of parts as will be hereinafter more fully described, illustrated in the accompanying drawings and claimed.

In describing the invention in detail reference will be had to the accompanying 30 drawings wherein like characters of reference designate like or corresponding parts throughout the several views, and in which:—

Figure 1 is a view of a fragment of a 35 door showing the improved key holder attached thereto, in elevation, Fig. 2 is an end view of the improved key holder, Fig. 3 is a detail perspective view of one element of the improved key holder, Fig. 4 is a detail 40 perspective view of another element of the key holder, and Fig. 5 is a cross sectional view on the line 5—5 of Fig. 3.

Referring more particularly to the drawings, 1 designates an ordinary door structure, which has any suitable type of ordinary lock 2 carried thereby, and a door knob 3, connected to the lock 2 for the manipulation of the catch. The shank 4 of the door knob 3 has a resilient band 5 mounted

thereabout, which band is provided with 50 an opening 6 extending therethrough, which opening receives the set screw 7, which normally holds the knob 3, against accidental movement upon the lock spindle (not shown), and it also securely binds 55 the resilient ring or strap 5 upon the shank 4.

The shank 4 has two radially projecting lugs 8 and 9 which extend from the circumference of the strap or ring 5, and they 60 are provided with transversely extending openings 10. The openings 10 are provided for the reception of the crooked end 11 of the rod 12. The rod 12 extends downwardly from the projections 8 and 9 and it is bent 65 so as to extend along one end and one side of a plate 14. The plate 14 is constructed of any suitable material, and it has a groove 15 extending along one end and one side thereof in which the rod 12 is seated, whereby the rod is securely connected to the plate, 70 for supporting the latter pendently of the door knob 3. The plate 14 is provided with a recess 16 formed in one side thereof and projecting transversely to the plate. The 75 opening or recess 16 is provided for the reception of the head of a key 17, so as to prevent the turning of the key when the head of the same is inserted in the recess. The rod 12 is loosely connected to the extensions 8 and 9, so that it may be moved 80 about for positioning the plate 14 for the reception of the head of a key.

In reducing the invention to practice certain minor features of construction, combination and arrangement of parts may 85 necessitate alterations to which the patentee is entitled provided such alterations are comprehended within the scope of what is claimed.

What is claimed is:—

In a key holder of the class described comprising a plate having a transversely extending recess formed therein for the reception of the head of a key to prevent the 95 turning or longitudinal movement of the key, said plate having a longitudinal groove along one end on one side thereof adapted

to receive a rod, said rod being bent at right angles to the plate, the terminal end of said rod being crooked, a resilient ring mounted around the shank of the knob, said resilient ring having a pair of radially projecting lugs extending from the circumference of the ring, said lugs being provided with a transverse opening adapted to loosely connect the crooked end of said rod and ring

for pendently supporting said plate beneath 10 the door knob.

In testimony whereof I affix my signature in presence of two witnesses.

NELSON D. NICHOLS.
